HAMMER

Arthur James Richardson and Edward James
Richardson, Baltimore, Md.

Application June 25, 1932, Serial No. 619,352

5 Claims. (Cl. 306—43)

This invention relates to an improvement in hammers, more particularly of the type employed by brick masons.

The object of the invention is to improve the character of a hammer of this type by making the blades removable for sharpening or the substitution of a sharpened blade or to prevent the edges of the blades from cutting through the sides of a tool bag in which the hammer may be carried. Another feature is the interlock between the blade and the end of the handle which prevents the head from flying off of the handle as it would otherwise occasionally do. The blade is secured to a flange of the head by a bolt which is set at an incline, so that when it is tightened up, it draws the end of the blade down into a notch at the end of the handle and effectively holds the parts together in interlocked relation.

In the accompanying drawing, Fig. 1 is a perspective view of the complete hammer;

Fig. 2 is a sectional view therethrough;

Fig. 3 is a similar view at right angles to Fig. 2, and taken through the head;

Fig. 4 is a perspective view of the handle shoe detached; and

Fig. 5 is a similar view of the blade.

The head of the hammer is designated by the numeral 1, and is shown as approximately square, being similar but somewhat larger than the head of the normal brick mason's hammer being provided with an opening 2 therethrough, which in this invention receives the solid end portion 3 of a handle shoe from the rear side of which projects strips 4. The handle 5 is received between the strips 4, and is secured thereto as by bolts or rivets 6. The strips 4 are somewhat wider where they join the portion 3 than said portion, providing shoulders 7 which abut against the back face of the head 1, to properly dispose the portion 3 in the head.

The solid end portion 3 is provided with a notch 8, in the upper side thereof, shown as slightly inclined to receive a tongue 9 formed on the lower end of a blade 10. The upper side of the head 1 is also provided with a notch 11 therein, in which the blade 10 is seated and an opening 12 extends from the notch 11 to the opening 2 to receive the tongue 9.

The head 1 is provided with an upstanding oblique flange 13 against which the blade 10 abuts. The blade is secured in place by a bolt 14, the head of which is preferably of polygonal 14 shape and fits in a similarly shaped groove 15 formed in the face of the blade 10, so that the

bolt will remain rigid while the nut 16 may be turned thereon to tighten up the bolt and may then be locked in place as by a lock washer and cotter pin. The bolt is set at an oblique angle so that when the nut is tightened up and the blade is drawn toward the flange 13, it also draws the tongue down tightly in the notch 8 to securely interlock with the handle shoe and hold the handle against removal. 5

By making the blades removable they may be taken out and sharpened or a new blade substituted without the necessity of temporarily losing the use of the entire hammer. The brick mason may carry several blades and substitute them whenever desired in a very simple manner. 15 Blades of different characters may be used instead of the form shown, such as picks, hammer claws, toothed blades, or the like. Any of these may be substituted for the blade in the hammer in a very simple manner or the blade may be removed and carried separately in the tool bag, so that it will not cut through the sides of the bag as it would if carried on the hammer. The use of a hammer of this character eliminates the necessity for a scotch or double-ended chisel. 25

In removing or replacing a blade, it is only necessary to remove the bolt 14, and then insert a new or sharpened blade or other tool in the notches 8 and 11, with the tongue 9, projecting through the opening 12 and into the notch 8, 30 and then replace the bolt which may be done very quickly and easily and the blade when in place securely holds the head on the handle and prevents it from flying off.

While we have developed this hammer primarily 35 for use by brick masons, nevertheless the features of our hammer may be used in other types of hammers as desired without departing from our invention.

We claim,

1. A hammer comprising a head having a handle receiving opening therein, a handle member fitted into said opening and having a transversely extending notch in the upper side thereof, a blade having a tongue arranged transversely of 45 the length of the handle member and extending into the upper side of the head and into said notch in interfitting relation with the handle member preventing removal thereof from the head, a flange upstanding from the head and receiving the blade in abutting relation, and means for removably securing the blade to the flange. 50

2. A hammer comprising a head having a handle receiving opening therein, a handle member fitted to said opening and having a notch ar- 55

- ranged transversely of the longitudinal axis thereof in the upper side thereof, said head having a transverse recess in the upper side thereof, and an opening extending downwardly from said recess to the handle receiving opening, a second member fitted in the recess in the head and having a tongue extending through the downwardly extending opening and into the notch in the handle member across its entrance path and preventing removal of the handle member from the head, and means extending through the second member and a part of the head for securing the second member to the head.
3. A hammer including a head, said head having a notch which extends thereacross and provided with an opening of restricted width which forms a continuation of the notch, the head having a flange, a blade fitted to the notch and resting against the flange and having a tongue which extends through the opening and into a handle, and means extending through the blade and flange for securing the blade to the head.
4. A device of the character described including a head and handle, the head having an integral upstanding oblique flange and provided with an oblique opening, one side of which is in line with one side of the oblique flange, the head provided

with a mortise and the handle with a tenon adapted to fit the mortise, and the handle having an oblique notch which registers with the opening in the head when the head and handle are assembled, a blade extending into the opening in the head, and into the notch in the handle, and lying obliquely against the flange, and means for securing the blade rigidly to the flange whereby the several parts are locked rigidly together.

5. A device of the character described including a head having a mortise extending in one direction, the head having an opening intersecting the mortise and provided with a notch leading to the opening, a handle, a shoe including a tenon adapted to enter and fit the mortise in the head, and provided with a notch in position and disposed to register with the notch in the head when the tenon is in the mortise, the shoe having side strips in position to embrace and be secured to the sides of the handle, a blade extending into the notch and opening in the head and into the notch in the shoe, and means for securing the blade to the head whereby all of the parts are interlocked and held rigidly together.

ARTHUR JAMES RICHARDSON.
